PROCESS FOR CONVEETING PETROLEUM
OILS

Walter M. Cross, Kansas City, Mo., assignor to
Gasoline Products Company, Inc., Newark,
N. J., a corporation of Delaware

Application July 24, 1930, Serial No. 470,435

5 Claims. (Cl. 196—51)

This invention relates in general to the treatment of petroleum hydrocarbons and more particularly has reference to a process of treating hydrocarbons in which the deposition of carbon 5 in the apparatus employed is avoided.

The deposition of carbon in various parts of oil treating apparatus has been recognized as an outstanding disadvantage in the treatment of hydrocarbon oils of high boiling point to convert 10 them into hydrocarbons of lower boiling points.

A major object of this invention is to provide a process in which hydrocarbon oil may be treated to convert the same into products of relatively low boiling point, and in which the deposition 15 of carbon on parts of the apparatus employed in carrying out the conversion is eliminated.

Another object of this invention is to provide a process of converting hydrocarbons in which the products of conversion are mixed with a cooling 20 medium prior to evaporating the same.

A further object of this invention is to provide a process of treating hydrocarbons in which hydrocarbons are subjected to conditions of conversion and in which the products of conversion 25 are mixed with a cooling hydrocarbon having a relatively high latent heat of vaporization and then introduced into an evaporating stage.

A still further object of this invention is to provide a process of treating hydrocarbon oils 30 wherein the products of conversion are combined with a cooling medium in the nature of a hydrocarbon oil, which serves to retard the evolution of vapors in a subsequent vaporizing zone, and to produce a residual material which may be removed from the system and utilized as fuel oil.

With these and other objects in view which may be incident to my improvements, the invention consists in the several method steps and the parts and combinations to be hereinafter set 40 forth and claimed, with the understanding that the procedure of the several necessary elements may be varied without departing from the spirit and scope of the appended claims.

In order to make my invention more clearly 45 understood, I have shown, in the accompanying drawing, means for carrying the same into practical effect without limiting the improvements in their useful applications to the particular constructions which, for the purpose of explanation, 50 have been made the subject of illustration.

In treating oil according to the process herein set forth, a charging stock may be placed under pressure by means of a pump 1 and forced into the heating elements of a furnace 2. As illustrated, the hydrocarbon oil undergoing treatment

is first passed through a preheating element 3, arranged in the upper portion of the furnace, and is then introduced into a lower heating element 4, wherein the oil is heated to a relatively high temperature. The construction of the heating elements 3 and 4 is such that the hydrocarbon oil will, of necessity, pass therethrough at a relatively high velocity. By causing the hydrocarbon oil to pass through the heating elements at a high velocity, deposition of carbon in the heating 10 elements will be avoided.

A relatively high pressure is maintained in the heating elements and the hydrocarbon passing therethrough is heated to a temperature sufficient to effect conversion of the oil. Due to the 15 rapid flow of the hydrocarbon oil through the heating elements, conversion of the oil is not effected, but the same is subjected to what may be termed incipient conversion.

Upon emerging from the heating elements 3 20 and 4, the oil under conditions of incipient conversion, is passed through a conduit 5 into a reaction chamber 6. This chamber is preferably of a size sufficient to permit a large body of the liquid hydrocarbon to collect therein and to remain therein for a time sufficient to consummate 25 the conversion instituted in the heating elements. Reaction chamber 6 may be heated and/or insulated against heat loss. I have shown a valve 7 in the conduit 5 by means of which a differential pressure may be established between the heating element 4 and the reaction chamber 6. Under normal operating conditions, however, this valve remains open so that the same pressure is maintained upon both the heating and reaction 30 stages. The oil within the reaction chamber 6 is maintained under a pressure sufficient to prevent any substantial vaporization of the oil therein. Under the above conditions, it will be found that substantially complete conversion of the hydrocarbon oil within the chamber 6 may be obtained.

Products of conversion may be withdrawn from the chamber 6 through the transfer line 8 controlled by valves 9 and 10, and introduced into 45 an evaporator 11 maintained at a pressure sufficiently low relative to that in the reaction chamber, so that an evaporation of the products of conversion is effected. Vaporized material emerges from the upper portion of the evaporator 50 and passes through the transfer line 12, into the lower portion of a refluxing tower 13, which is of any construction suitable for dephlegmating vapors of the character passing through line 12. Effluent passing from the upper portion of tower 55

13 is conveyed through line 14 to a gas separator 15, the liquid material being transferred to the gasoline tank 16, and the gases passing off through the gas outlet 17. Unvaporized material collects in the lower portion of the evaporator, and upon reaching a predetermined height, actuates a mechanism 18, which controls an outlet valve 19 in a discharge line 20. The discharge line is adapted to convey unvaporized material from the lower portion of the evaporator through cooler or condenser 24, to the fuel oil tank 21.

Refluxing tower 13 is provided with an automatic outlet control mechanism 18' which controls an outlet valve 19' in a discharge line 20'. The reflux condensate may pass through conduit 22, controlled by valve 23, through the condenser 24 and into a storage tank 25, or may be passed through conduit 26 into a collecting tank 27 without being subjected to cooling in the chamber 24. The reflux condensate may be passed directly from tank 27 by means of the line 28 to the charging pump 1, to be forced through the cracking system.

If the products of conversion pass directly from the reaction chamber to the evaporator, a large portion of the material will be vaporized, leaving a coke-like or asphalt-like bottom in the vaporizing chamber 11, which is relatively useless as a commercial product. In certain instances wherein an excessive amount of material has passed overhead, the bottom remaining in the vaporizing chamber contains an excessive amount of free carbon that may be difficult to readily eliminate from the system.

By introducing an extraneous medium such as a refrigerant, which may or may not be a hydrocarbon oil, through the line 29, and combining it with the heated products of conversion, the vaporization in the chamber 11 may be retarded to the desired degree, permitting only those fractions to pass overhead which may be utilized as a recharging stock when separated out in the dephlegmator, and such lighter products as may subsequently be collected as final distillate. As mentioned, this medium serves not only to retard vaporization and retain a larger quantity of the oil as a bottom in the vaporizing stage, but also serves to increase the fluidity of the bottom, giving a blended product which has properties ranging between those of the natural fuel oil and the bottoms recovered from the cracking operation. Among other properties, this blending will lower the cold test of the bottoms, which is normally too high when certain types of oils are employed as charging stocks.

The present invention contemplates the introduction as a refrigerant to retard the vaporization of the products of conversion, any substance which may be found suitable for the purpose. For instance, any of the well known refrigerants, preferably those which would not detrimentally react with the material undergoing treatment may be used. These refrigerants may or may not be miscible with the material undergoing treatment.

In certain instances, it may be found advantageous to liquefy the uncondensable gases resulting from the process, and introduce these liquefied gases into the stream of products of conversion passing to the evaporator. These gases may include methane, ethane, unsaturated hydrocarbons and mixtures of the same.

Another distinct method of avoiding the deposition of carbon is to withdraw a portion of

the oil undergoing conversion and reintroduce it into the chamber in such a manner as to scavenge or sweep the surfaces of the chamber upon which carbon is likely to deposit. This may be accomplished by withdrawing the oil through a conduit 30, connected with the intake side of a suitable pump 31, and forcing it through a conduit 32 associated with a spraying device positioned within the reaction chamber 6.

It will be appreciated that I have provided a process wherein a refrigerant or cooling agent may be introduced into the synthetic crude taken from the reaction zone, so as to avoid excessive vaporization of the synthetic crude upon release of pressure and produce a product from the unvaporized material which may be used as a fuel oil.

While I have shown and described the preferred embodiment of my invention, I wish it to be understood that I do not confine myself to the precise details of construction, as it is apparent that many changes and variations may be made therein, by those skilled in the art, without departing from the spirit of the invention, or exceeding the scope of the appended claims.

I claim:

1. A method of converting hydrocarbon oils to obtain hydrocarbons having lower boiling points, comprising heating the oil while passing through a heating element at a rate sufficient to prevent the deposition of carbon on the walls of the element, to a temperature and under a pressure sufficient to bring about incipient conversion of the oil, passing the oil under these conditions to an enlarged reaction chamber containing a large body of the oil, and wherein conversion may be consummated, withdrawing products of conversion from the chamber, introducing the products of conversion together with a liquefied gas refrigerant into an evaporating stage, dephlegmating the vapors resulting from the evaporation, and removing the unevaporated material from the evaporating stage.

2. A method of treating hydrocarbon oils to convert higher boiling hydrocarbons into lower boiling ones, which comprises subjecting the oil in a cracking zone to a cracking temperature sufficient to convert higher boiling hydrocarbons into lower boiling ones, maintaining the oil in said cracking zone under a pressure sufficient to maintain it in the so-called liquid phase, withdrawing the converted products from said cracking zone and introducing the same into an evaporating zone wherein the vapors and non-volatile constituents are separated, and cooling the liquid introduced into the evaporating zone with a liquid which is a gas at normal temperature and pressure.

3. In the treatment of hydrocarbon oils in which the oil is subjected to cracking conditions of temperature and pressure to convert higher boiling hydrocarbons into lower boiling hydrocarbons and the products of conversion are subsequently passed in a regulated stream to an evaporating zone wherein a selected portion of the products are evaporated; the improvement which comprises introducing a liquid which is a gas at normal temperature and pressure into the stream of converted products being passed to the evaporating zone.

4. In the treatment of hydrocarbon oils in which the oil is subjected to cracking conditions of temperature and pressure to convert higher boiling hydrocarbons into lower boiling ones and the products of conversion are then passed to an

evaporating zone, the improvement which comprises introducing a hydrocarbon liquid which is a gas at normal temperature and pressure into the conversion products passed to the evaporating zone.

5. In the process of converting hydrocarbons into products suitable for motor fuel, the improvement which comprises heating a confined

stream of hydrocarbons to a temperature adequate to effect conversion of hydrocarbons into motor fuel products and thereafter introducing into said stream a cooling medium comprising a liquid which is a gas at normal temperatures and pressures. 5
